GARMENT BAG

Leonce Schwartzman, Baltimore, Md., assignor
to Protex Products Company, Inc., Jersey City,
N. J., a corporation

Application March 16, 1943, Serial No. 479,336

8 Claims. (Cl. 206—7)

This invention relates to garment bags.

An object of this invention is to provide a bag of the character described which may be supported on the usual horizontal closet clothes rod, the construction being such that the garment hangers also may be engaged on the rod and within the bag, thus eliminating the frames of garment bags heretofore used on which the garment hangers were hung, and also eliminating the usual hooks on such frames which engaged the closet rod, thus saving in metal, while providing a strong support for the garments.

A further object of this invention is to provide a garment bag having means to support the bag on the usual closet clothes rod, without necessity for hooks, the construction being such that the bag may be made of any desired width and permitting the bag to be shifted sideways on the rod. With such construction the weight of the garments is on the closet rod or pole and not on any part of the bag. Furthermore, it is easier to hook the garment hangers on the closet rod than on the usual garment bag frames used heretofore.

Still another object of the present invention is to provide a garment bag of the character described having a closure which normally remains closed without necessity for the usual slide fastener heretofore used and which closure is dust proof and moth proof.

Yet another object of this invention is to provide a garment bag of the character described having a longitudinal opening through which garments are inserted in the bag, the material on opposite sides of the opening interfolded in such a way so as to close the garment bag without necessity for other fastening devices.

Yet another object of this invention is to provide a strong and durable garment bag of the character described which shall be relatively inexpensive to manufacture, easy to manipulate and which shall yet be practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which is shown one of the various possible illustrative embodiments of this invention,

Fig. 1 is a perspective view of a garment bag

embodimenting the invention, hung on a closet rod;

Fig. 2 is a transverse cross-sectional view of the bag;

Fig. 3 is a cross-sectional view taken on line 3—3 of Fig. 2;

Fig. 4 is a cross-sectional view taken on line 4—4 of Fig. 2;

Fig. 5 is a cross-sectional view taken on line 5—5 of Fig. 1;

Fig. 6 is a perspective view of the top frame for the garment bag; and

Fig. 7 is a view similar to Fig. 6 but showing a modified construction.

Referring now in detail to the drawings, 10 designates a garment bag embodying the invention hung on the usual horizontal closet clothes rod 11 on which garments on hangers are usually hung. The rod 11 is rigid and strong, and as shown hereinafter, the garments may be inserted within the bag and suspended on said rod.

The bag 10 may be made of any suitable soft or flexible sheet material such as cloth, Pliofilm, Cellophane or other material. The same is generally prismatic in shape and has parallel side walls 14, a bottom wall 15 and a rear wall 16, stitched together by seams 17 and 18 at the bottom and rear edges of the bag, respectively. Stitched to the front edges of side wall 14 as at seams 19 and 20, are overlapping, interfolded sheets 21 and 22 forming a closure for the front of the bag, as will be described hereinafter. Said sheets 21, 22 are stitched to the front edge of the bottom wall 15 by the seam 17 which extends all around the peripheral edge of the bottom wall.

Stitched to the upper edge of the front, side and rear walls is a top wall formed in two parts designated by numerals 24 and 25. The front part 24 is stitched to the upper edge of the side walls 14 at seams 26 and to the upper end of the sheets 21, 22 by the seam 27. The rear part 25 is stitched to the upper end of the rear wall 16 by seam 28, and to the upper edge of the side walls 14 by seams 29. The inner ends of parts 24, 25 overlap as shown in Fig. 4 of the drawings and are attached together by any suitable releasably fastening means such as snap fastener 30. If desired the snap fasteners may be replaced by tie cords.

The top wall of the garment bag is thus split 50 transversely across the middle. The side walls 14 are also notched downwardly from the upper ends thereof at the middle, as at 33, to permit the rod 11 to pass downwardly between the top wall parts 24 and 25 and into the notches in the side walls.

Extending downwardly from the side edges of top wall 24 are flaps 35 stitched to side walls 14 as at 35a adapted to close the notches 33 above the rod 11 so as to engage the rod to prevent dust from entering the bag.

There is also attached to the top wall part 25 flaps 36 likewise stitched to said side walls 14 as at 36a and overlapping the flaps 35. The overlapping flaps thus substantially seal the bag at the openings through which the rod passes.

Received and fitted within the top of the bag, and mounted on the rod 11 is a frame 40 made of card board, paper board, composition or any other suitable stiff material. Member 40 has a top wall 41 contacting the underside of top wall 24, side walls 42 located adjacent the inside of side walls 14, and end walls 43 adjacent the front and rear walls of the bag. The side walls 42 have similar, aligned semi-circular notches 44 at the mid-portions thereof extending to the lower edges 45 of said side walls. The height of member 40 is such that when the rod 11 is received within the notches 44 the top wall 41 will snugly fit against the under surfaces of the top wall parts 24, 25 there being enough clearance to permit insertion of the frame.

In mounting the bag on the rod the parts 24, 25 are unfastened and opened up. The rod is then moved through the opening in the top wall and down into the notches 33. The frame 40 is then passed through the opening at the front of the bag which is produced by opening up the sheets 21, 22 in the manner hereinafter appearing, and slipping the frame member above the rod and beneath the top wall of the bag to fit within the top of the bag, so that the rod 11 engages within the notches 44.

It will now be understood that the bag is supported on the rod 11 and may be shifted sideways. It may be made of any desired width. No hook is necessary for mounting the bag on the rod 11. Garments on garment hangers may be inserted into the bag and hung directly on the rod 11. Thus the usual frame which supports the garment hangers in garment bags heretofore made are entirely eliminated.

The closure for the front of the bag will now be described. This closure comprises the sheets 21, 22. The sheet 22 comprises a front portion 50 extending from the seam 20 about $\frac{3}{4}$ of the width of the front of the bag towards the seam 19, and extending therefrom is a folded back portion 51 which is folded inwardly about fold 74. The sheet 21 comprises a portion 52 which extends from the seam 19 toward the seam 20 and overlaps the inner side of sheet 22. The portion 52 extends just beyond the inner edge of portion 51 of sheet 22. Extending therefrom is a folded back portion 53 folded about fold 53a and located between sheet portions 50 and 51 of sheet 22. Extending from the sheet portion 53 is a folded back portion 54 which is folded about fold 54a and contacts the sheet portion 53 and also contacts the inner surface of sheet portion 51. The sheet portion 51 is thus disposed between the sheet portions 52 and 54. It will be understood that the sheet portions 21 and 22 with all their folds are stitched together at the top and bottom by the seams 27 and 17, respectively.

There is thus provided an airproof and moth proof closure for the front of the bag.

To open the bag it is necessary to unfold the folds at the front of the bag. When the folds are released they will fold together again and thus close the bag.

As shown in Fig. 7 of the drawings the side walls 42 of the frame member 40 may be provided with curved, semi-circular plates 70 hinged thereto as at 71, adjacent the notches 44. Member 70 may be pivotally moved to engage the lower portions of the rod 11 to aid in closing the openings or notches 33 through which the rod passes.

A plurality of pairs of tie strings 72, 73 may be stitched to the seam 19 and folded edge 74 of sheet 22. Each pair of tie strings may be tied together to retain the bag in closed condition.

A card board stiffener 80 may be placed within the bottom of the bag as shown in Fig. 2 of the drawings.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention, I claim as new and desire to secure by Letters Patent:

1. In combination, a garment bag having openings in its side walls adjacent its top wall, a rod passing through said openings, and a member within the bag interposed between the rod and the underside of the top of the bag, said member resting on said rod and being supported thereby and having portions resting upon the rod, said member having a portion located above the portions which rest upon the rod, and contacting the underside of the top wall of the bag to keep said top wall spaced above said rod, and said bag being suspended on said member, whereby said rod supports said member and bag.

2. In combination, a garment bag having aligned openings in a pair of its opposite side walls adjacent its upper end, a rod passing through said openings, and a member within the bag interposed between the rod and the underside of the top of the bag, said member resting on said rod, said bag being supported by said member, said member having a top wall and side walls extending downwardly from the top wall, said side walls having their lower edges formed with downwardly opening notches engaging said rod.

3. A bag having side walls and a top wall, said top wall being open transversely, and said side walls having notches on their upper ends communicating with said openings in the top wall, a rod passing through said notches, means to close the opening in the top of the bag, and a member having means contacting the underside of the top wall of the bag and means contacting said rod, said bag being suspended on said member, and said member being supported by said rod, whereby said rod takes the weight of both the member and the bag the means which contacts the top wall of the bag being disposed above the means which contacts the rod whereby to space the top wall of the bag above said rod.

4. A garment bag split transversely across the top, the upper ends of the sides of the bag being notched at the split, a rod passing through the notches in the sides of the bag, means to releasably close the split in the top of the bag, and a frame within the bag interposed between the rod and the top of the bag, said frame and bag being supported on said rod, said frame having a top wall, side walls, and end walls, said side walls

having their lower edges formed with downwardly opening aligned notches to receive and engage said rod.

5. In combination, a garment bag having aligned openings in a pair of its opposite side walls adjacent its upper end, a rod passing through said openings, and a member within the bag interposed between the rod and the underside of the top of the bag, said member resting on said rod, said bag being supported by said member, said member having portions formed at their lower edges with downwardly opening notches engaging said rod.

6. In combination, a garment bag, a rod passing through said bag whereby garment hangers may be hung in the bag and directly on said rod, and means interposed between said rod and the top of the bag and having portions resting on and contacting said rod and a portion contacting the underside of the top of the bag to space the top of the bag from said rod and to suspend the bag from said rod and to space the top of the bag above said rod.

7. In combination, a garment bag, a rod passing through said bag whereby garment hangers may be hung in the bag and directly on said rod, and means interposed between said rod and the top of the bag to space the top of the bag from said rod and to suspend the bag from said rod, said means comprising a frame fitting the top of the bag and having downwardly opening means to engage said rod.

8. In combination, a garment bag having aligned openings in its opposite sides near the top thereof, a supporting rod extending through said aligned openings, a unit arranged entirely within the top of the bag and having face contact with the top thereof, said unit including depending portions resting on said supporting rod for holding the bag distended and the top of the latter in spaced relation to said rod, said unit constituting the sole means for supporting the bag on the rod.

LEONCE SCHWARTZMAN.
